UNITED STATES PATENT OFFICE.

THOMAS V. WILSON, OF WYOMISSING BOROUGH, PENNSYLVANIA, ASSIGNOR TO TEXTILE MACHINING WORKS, OF WYOMISSING, PENNSYLVANIA, A CORPORATION OF PENNSYLVANIA.

BRAIDING-MACHINE CARRIER.

1,261,983.

Specification of Letters Patent. Patented Apr. 9, 1918.

Application filed May 11, 1915. Serial No. 27,306.

To all whom it may concern:

Be it known that I, THOMAS V. WILSON, a citizen of the United States, residing at borough of Wyomissing, in the county of 5 Berks and State of Pennsylvania, have invented certain new and useful Improvements in Braiding-Machine Carriers, of which the following is a specification.

My invention relates to bobbin-holding devices having means for controlling the tensioning and let-off of the thread; and it consists in the improved construction herein-after described, the novel features of which are specifically pointed out in the claims.

15 The drawing shows the invention applied to a traveling bobbin carrier such as is employed in braiding machines, though the invention is equally applicable where the rotatable bobbin or supply holder is carried 20 upon a fixed supporting frame.

Figure 1 is an elevation of a device embodying my invention in preferred form; extreme positions of the thread-tensioning lever being indicated in dotted lines.

25 Fig. 2 is a sectional view similar to Fig. 1. The braiding machine carrier indicated is of a well known type, having a supporting frame 7 with a foot portion comprising spaced plates 2, 2 connected by a heart or 30 shuttle piece 3, and a downwardly extending pin 4 to engage the drive gears of a braiding-machine. A threading standard or stem 5, and a supply-holder standard or spindle 6, form rigid portions of the frame.

35 A supply-holder let-off device in the form of a pawl 8, is loosely strung upon the spindle 6 and pivotally supported at the foot of the latter, upon lateral projections 9 on the frame 7, so as to be rockable upon said 40 supporting projections. This pivoted let-off device 8 forms a seat for a cylindrically coiled spring 10, which is strung upon the spindle 6 above it and secured to the spindle at one end so as to exert endwise pressure 45 upon said rockable device to normally maintain it in horizontal position; the pressure thus exerted being definitely regulated, as indicated, by providing a plurality of notches 11, 11 in the spindle 6 for adjustably engaging a set screw 12 in the spring collar 13.

The let-off pawl device 8 indicated, is provided with a detent projection 15, adjacent one end, adapted to engage the toothed base portion 16 of a tubular thread-supply

holder 17; which holder is adapted to rotatably inclose the adjustably secured spring 10 on the spindle 6, and comprises a suitable wrapping or cop of thread 17^a.

As indicated the thread 18 extending from the holder 17 is passed through a guide eye 19 in the stem 5; then through a second guide eye 20 of a lever 21; and finally through a terminal guide eye 22 of the stem. Said lever 21 is arranged to serve both as a tensioning lever for the thread, and as a 65 means for releasing the supply holder 17 by operation of the holder engaging device 8, so as to let off thread as required; the spring 10 serving to control both these functions.

70 The pivot end of the lever 21 is shown fixed to a pivot shaft 25, which extends through pivot jaws 26 of the frame 7, and is provided between said jaws with a cam projection 27 adapted to operatively engage 75 the adjacent end portion 28 of the pivoted let-off device 8; so that swinging movement imparted to the lever by tensioning of the thread 18 will exert a rocking action on said device against the seating pressure of the 80 spring 10. This rocking movement of the let-off device as the lever is raised, tends to release the supply holder from the detent projection 15 at the other end of the device, both by depressing the latter and by raising 85 the holder as shown. In order that the final releasing movement of the pawl-shaped let-off device 8 may be quickened, as I have found to be advantageous under some conditions, I provide for changing the leverage 90 at which the lever 21 operates to rock it, by employing a stepped arm or cam projection 27, the outer step 27^a of which comes into action against the pawl device when the supply holder is nearly released, as in the position illustrated in the drawing.

95 The lever 21 is provided with a stop projection which is dropped into the path of a stop-motion mechanism in case of thread breakage, as usual. It will be readily seen 100 that owing to the co-operative arrangement of the let-off device 8 and the lever 21 with the spring 10, the latter serves to satisfactorily control both the thread tensioning and the bobbin-releasing action; and that the 105 location, regulation, and operation of the spring are simple and advantageous. The preferred construction specifically set forth

may be readily modified without departing from the essentials of the invention as defined in the claims.

What I claim is:

- 5 1. In combination with a carrier frame having a fixed spindle, a tensioning let-off spring cylindrically coiled upon said spindle, a rotatable supply holder inclosing said spring, a pivotally mounted holder-controlling device forming a seat for said spring, and a thread-tensioning lever arranged in constant operative engagement with said device.
  - 10 2. In combination with a carrier frame having a fixed spindle, a tensioning let-off spring cylindrically coiled upon said spindle and adjustable thereon to vary the tension, a rotatable supply holder inclosing said spring, a pivotally mounted holder-controlling device forming a seat for said spring, and a thread-tensioning lever arranged in constant operative engagement with said device.
  - 15 3. In combination with a carrier frame having a fixed spindle, a tensioning let-off
  - 20
- spring cylindrically coiled upon said spindle, a rotatable supply holder inclosing said spring, a holder-controlling pawl lever intermediately pivoted and forming a seat for said spring, and a thread-tensioning lever arranged to impart a rocking movement to 30 said spring-pressed pawl lever.
4. A carrier frame having a fixed spindle provided with a cylindrically coiled spring one end of which is fixed thereto, a supply holder rotatably mounted upon said spring-provided spindle, a let-off device pivotally mounted on said frame and controlled by end-wise pressure of said spring, and a thread-engaging lever adapted to operate said spring-pressed device and to be tensioned thereby.
5. A carrier frame, a toothed supply holder rotatable thereon, a spring-pressed pawl for said holder, and a thread-tensioning pawl lever adapted to produce a quickened final releasing movement of the pawl.

In testimony whereof I affix my signature,
THOMAS V. WILSON.
